UNITED STATES PATENT OFFICE.

SOLOMON C. SPRING, OF BRISTOL, ASSIGNOR TO THE E. N. WELCH MANUFACTURING COMPANY, OF FORESTVILLE, CONNECTICUT.

DESIGN FOR A CLOCK-CASE FRONT.

SPECIFICATION forming part of Design No. 15,500, dated October 28, 1884.

Application filed August 21, 1884. Term of patent 14 years.

To all whom it may concern:

Be it known that I, SOLOMON C. SPRING, a citizen of the United States, residing at Bristol, in the county of Hartford and State of Connecticut, have invented and produced a new and original Design for a Clock-Case Front, of which the following is a specification, reference being had to the accompanying drawing, forming part thereof.

10 Said drawing shows a front elevation of my newly-designed clock-case front.

15 A designates the base, consisting of a series of moldings or bands, the lower one of which is cut away, and in the middle of the cut-away portion is a valance-like projection, *a*, having a scalloped or indented lower edge. The middle one of these moldings and the lower one at each end are ornamented by a series of carved or sunken lines, as shown.

20 B designates the sash or door, the main portion of which consists of a rectangular frame

or sash, *b*. Upon the side edges of this sash, and extending to the upper and lower corners, are ornamental brackets *c d*, respectively. All of these brackets have an upright portion 25 which is parallel to the upright rails of the sash, and in the upper bracket, *c*, this upright portion is separated from the sash-rails, so as to leave an open space between. The contour of these brackets is clearly shown, and they 30 are ornamented by sunken or carved lines.

C designates the cap of the case, consisting of moldings and open bracket-work, ornamented by carved or sunken lines, all as shown.

35 I claim--

The design for a clock-case front herein shown and described.

SOLOMON C. SPRING.
